UNITED STATES PATENT OFFICE.

HERMAN F. VOSHARDT, OF CHICAGO, ILLINOIS, ASSIGNOR TO FRIEDELEY VOSHARDT CO., OF CHICAGO, ILLINOIS, A CORPORATION OF ILLINOIS.

DESIGN FOR A PLATE FOR LIGHTING FIXTURES.

Application filed January 2, 1925. Serial No. 11,849. Term of patent 7 years.

To all whom it may concern:

Be it known that I, HERMAN F. VOSHARDT, a citizen of the United States, residing at Chicago, in the county of Cook and State of Illinois, have invented a new, original, and ornamental Design for a Plate for Lighting Fixtures, of which the following is the specification, reference being had to the accompanying drawing, forming part thereof.

Fig. 1 is a side elevation of a plate for lighting fixtures, showing my new design.

Fig. 2 is a bottom view of the same.

I claim:

The ornamental design for a plate for lighting fixtures, as shown.

HERMAN F. VOSHARDT.
